Primary Examiner — Phillip S Hyder(74) *Attorney, Agent, or Firm* — Hubbard Johnston, PLLC(57) **CLAIM**

The ornamental design for a bit breaker top and bottom, as shown and described.

DESCRIPTION

FIG. 1 is a top perspective view of the bit breaker top and bottom showing my new design in an assembled condition; FIG. 2 is a perspective view thereof, in a disassembled condition; and, FIG. 3 is a bottom perspective view thereof.

The broken lines depict portions of a bit breaker, in which the design is embodied, but which are not considered part of the claimed design.
